UNITED STATES PATENT OFFICE.

HECTOR E. BRUNELLE, OF MANCHESTER, NEW HAMPSHIRE.

TOBACCO-BOX.

1,384,937.

Specification of Letters Patent. Patented July 19, 1921.

Application filed December 2, 1919. Serial No. 341,873.

To all whom it may concern:

Be it known that I, HECTOR E. BRUNELLE, a citizen of the United States, residing at Manchester, in the county of Hillsborough 5 and State of New Hampshire, have invented certain new and useful Improvements in Tobacco-Boxes; and I do hereby declare the following to be a full, clear, and exact description of the invention, such as will enable others skilled in the art to which it 10 pertains to make and use the same.

This invention relates to tobacco boxes and more particularly to pocket tobacco boxes, and the primary object of the invention 15 is to provide an improved means for facilitating the removal of the tobacco from the box.

Another object of the invention is to provide attachments for tobacco boxes, for 20 moving the envelop containing the tobacco upward, as the tobacco is used therefrom.

Another object of the invention is to provide a follower arranged in the bottom of a tobacco can below the envelop carrying 25 the tobacco and having means for raising the follower when desired, so as to force the envelop upward and outwardly when desired.

Another object of the invention is to provide 30 an improved means for holding the follower in any adjusted position so as to hold the envelop at the desired height.

A still further object of the invention is to provide an improved device of the above 35 character, which is durable and efficient in use, one that is simple, and easy to manufacture, and one that can be placed upon the market at a reasonable cost.

With these and other objects in view, the 40 invention consists in the novel construction, arrangement and formation of parts, as will be hereinafter more specifically described, claimed and illustrated in the accompanying drawing, forming a part thereof, in which—

Figure 1 is a side elevation of a tobacco can showing the attachment applied thereto,

Fig. 2 is a vertical section showing the envelop in a partly raised position,

Fig. 3 is a horizontal section taken on 50 the line 3—3 of Fig. 3,

Fig. 4 is a fragmentary end elevation illustrating a catch for securing the free ends of the cord,

Fig. 5 is a detail section showing a modified form of the device.

Referring to the drawing in detail, where-

in similar reference characters designate corresponding parts throughout the several views, the numeral 1 indicates a pocket tobacco can of the ordinary or any preferred form and includes a body 2 having the lower wall 3 and a cover 4 hingedly connected to the upper edge thereof.

The can 1 has mounted therein the usual tobacco carrying envelop 5.

The attachment 6 for raising the envelop outward of the can includes a follower or false bottom 7 which is slidably mounted in the can below the tobacco carrying envelop. The false bottom is shaped to conform to the configuration of the body and is provided with a central longitudinally extending groove or guideway 8 in its lower surface for the reception of the pulling cord 9 which will be hereinafter more fully described. The follower or false bottom 7 may be made of any preferred material such as tin, heavy card-board or the like, and has formed therein adjacent each end thereof, openings 10 through which the terminals of the pulling cord 9 extend. The side walls of the can 1 adjacent the upper edge thereof are provided with openings 11 through which the cord is threaded and one terminal of the cord is knotted as at 12 to prevent the same from being pulled through the opening. The opposite wall in the can 1, directly below the opening 11 is provided with a struck out tongue 13, which is bent back upon the can so as to form a spring clip, and the free terminal of the pulling cord is adapted to be positioned under the clip so as to hold the cord in any position and the tobacco envelop in its raised adjusted position.

It will be seen that the cord 9 is threaded through the openings 10 in the follower 7 and positioned in the guide groove and extended upwardly between the side walls of the can and the envelop and then through the openings 11.

In operation of the improved device, when it is desired to raise the envelop out of the can after tobacco has been used from the top thereof, the terminal of the cord opposite to the knotted end 12 thereof is pulled, which raises the follower or false bottom 7 upwardly. The free terminal of the cord is then positioned under the clip 13 which will hold the follower in raised position and the tobacco carrying envelop in its adjusted position.

In Fig. 5 is illustrated a modified form of

the device in which the bottom wall of the can is dispensed with and the same is provided with merely an inwardly extending flange 15 which serves to limit the downward movement of the follower. In other respects the can attachment is identical with the construction disclosed in Figs. 1 to 4.

In this form of can it is impossible to refill the can with loose tobacco as it will be seen that the tobacco will fall between the false bottom or follower and flange 15, and thus the can is in the nature of a non-refillable device.

In practice, I have found that the form of my invention, illustrated in the accompanying drawing and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required

without sacrificing any of the advantages of my invention as set forth.

What I claim as new is:—

A tobacco box including a receptacle having an opening in opposite walls adjacent their upper ends, a follower slidably mounted in the receptacle and having openings adjacent its end and a groove in its under face connecting said last named opening, a cord extending through one of the first named openings and having one end tied 35 in a knot to prevent said cord from being pulled through said first opening, said cord passing through said second named openings and resting in the groove and passed through one of the first named openings, 40 and a catch carried by the receptacle to engage the free end of the cord.

In testimony whereof I affix my signature in presence of two witnesses.

HECTOR E. BRUNELLE.
